WILLIAM SUTHERLAND AND THOMAS I. LEWELLEN, OF PHILADELPHIA, PENNSYLVANIA.

Design No. 3,401, dated March 2, 1869.

DESIGN FOR A FLOWER-POT.

The Schedule referred to in these Letters Patent and making part of the same.

To all whom it may concern:

Be it known that we, WILLIAM SUTHERLAND and THOMAS I. LEWELLEN, of the city and county of Philadelphia, in the State of Pennsylvania, have invented or produced a new and original Design or Ornament to be applied to the Duplex Plant or Flower-Pot, or Vase, or other similar fabrics, consisting of equal similar corrugated flutes, placed vertically all round the outer circumference of the exterior vase or pot, and extending from the bottom to a horizontal figure, represented by a grape-vine, which encircles and terminates this circumference-part, surmounted by a scroll, represented on the flanged lip of the inner vase, which extends all round over the outer one, of which the following is a full, clear, and exact description, reference being had to the accompanying drawing, which exhibits an exterior view of the ornamented pot or vase, which drawing makes part of this specification, and in which—

A is one of the similar corrugated flutes;

B, the grape-vine, encircling the upper part of the outer circumference of the exterior vase or pot; and

C, the scroll, on the flanged lip of the inner vase or pot.

These vases or pots may be made of any approved

form, of metal, earthenware, glass, or other suitable material, and the figures of such magnitude and proportion as to be adapted to the size of the fabric to which they are to be applied.

The ornaments, thus described, may be applied to the pot, vase, or other fabric, by casting, moulding, planching, or other convenient process, in low, medium, or high relief, as may be desirable, thus forming an ornate, beautiful article of furniture, for standing or suspending in the parlor, conservatory, or garden, instead of the unsightly fabrics now in use.

What we claim as our invention, and desire to secure by Letters Patent, is—

The design or ornament for plant or flower-vases, pots, or other similar fabrics, as and for the purposes hereinbefore described.

In witness whereof, our names are hereunto subscribed, this 12th day of February, 1869.

WILLIAM SUTHERLAND.
THOMAS I. LEWELLEN.
